[57] ABSTRACT

The present invention relates to devices for the electroslag casting of ingots. The device is characterized in that the non-consumable cooled metal electrode used for melting the ingots is washed with gas flows, with the gas being used for washing only that portion of the electrode which is immersed in the melt, thus providing a protecting envelope about this portion. This prevents the non-consumable electrode from electrochemical destruction.

DEVICE FOR THE ELECTROSLAG CASTING OF INGOTS

BACKGROUND OF THE INVENTION

This is a Rule 60 continuation application of Ser. No. 130,412, filed Apr. 1, 1971, now abandoned.

The present invention relates to the field of special electrometallurgy and, more particularly, the invention relates to a device for the electroslag casting of ingots. The invention can be used in the process of making steels and alloys.

PRIOR ART

Well known in the art is a method of electroslag casting of ingots by means of non-consumable graphite or silite electrodes fed with direct or alternating current.

However, the graphite and silite electrodes are not non-consumable and in the process of electroslag casting such electrodes, when subjected to the action of high temperatures and the chemical effect of the slag, are gradually dissolved thus contaminating the slag melt with foreign inclusions, i.e. with the products of dissolution of the electrodes.

Therefore, the metals being remelted are saturated with carbon, silicon, and deleterious impurities including sulphur, phosphorus, etc., and this results in deterioration of the ingot metal quality.

Investigations have shown that it is expedient to use non-consumable cooled metal electrodes for electroslag remelting of metals by means of a straight-polarity direct current. The application of such electrodes prevents the remolten metal from saturation with deleterious impurities.

However, such electrodes, especially when fed with an alternating current or a reversed-polarity direct current, are subjected to electrochemical destruction and this also leads to the contamination of the melt with foreign impurities, resulting in premature wear of the electrode itself.

The same undesirable result occurs when casting hollow ingots. In this case, the cooled metal electrode, such as a pan for shaping the inner space of the blank, is also subject to electrochemical destruction.

OBJECTS AND SUMMARY OF THE INVENTION

An object of the present invention is to eliminate the above-mentioned disadvantages.

The specific object of the invention is to provide a device for the electroslag casting of ingots by means of which it is possible to prevent the electrochemical destruction of the non-consumable cooled metal electrodes, thus increasing the life thereof, and also enhancing the purity of the metal being remelted.

This object is attained due to the fact that in the electroslag casting of ingots by means of a non-consumable cooled metal electrode, according to the present invention, the portion of the non-consumable electrode immersed in the melt is washed with gas flows under pressure.

This makes it possible to eliminate the electrochemical destruction of the non-consumable electrodes.

In the present device including a non-consumable cooled metal electrode provided with openings located in the portion of the electrode immersed in the melt, according to the invention, on the end wall of this portion of the electrode there are provided grooves guiding the flow of gas bubbles admitted from the above-

said openings over the whole surface of the immersed portion of the electrode, thereby preventing it from electrochemical destruction.

The end wall of the immersed portion of the electrode is preferably convex in shape. This provides for smooth washing of the entire portion of the electrode immersed in the melt with the gas flows, which create protective envelope.

The present device made according to the invention successfully solves the previously described technical problem.

The invention will be further described in detail with reference to the accompanying drawings, in which:

BRIEF DESCRIPTION OF THE DRAWINGS

FIG. 1 is an elevational view of a device for electroslag casting of ingots;

FIG. 2 is a bottom view of the non-consumable metal electrode;

FIG. 3 is a sectional view taken along the line III—III in FIG. 2;

FIG. 4 is a general view of a device for electroslag melting of hollow ingots; and

FIG. 5 is a view taken along the line V—V in FIG. 4, the view looking in the direction of the arrows.

As shown in FIG. 1, the device for electroslag casting of ingots includes a cooled mold 1, a cooled pan or bottom plate 2, a non-consumable cooled metal electrode 3 and consumable electrodes 4. The non-consumable electrode 3 has a sidewall 3a, end wall 3b and a bore 3c. The end wall 3a and the side wall adjacent thereto is provided with opened end grooves 7 with the grooves 7 being provided with openings 6 which communicate with the bore 3c of the electrode. The portion of the electrode 3 provided with the openings 6 and grooves 7 is immersed into a slag bath 5 (FIGS. 1-3). The device is fed from a power supply source 8 inserted between the non-consumable electrode 3 and the pan 2.

The device operates as follows:

Prior to starting the electroslag process, the non-consumable electrode 3 is placed in the mold 1, with cooling liquid 9 and gas 10 (or a gas mixture) being fed into the bore 3c of the electrode. Molten slag is poured into the mold 1 to form a slag bath 5. The gas 10 is fed

through the openings 6 in the non-consumable electrode 3 as a flow of gas bubbles 11 directed to the zone of the slag bath 5 surrounding the non-consumable electrode 3, so that a gas envelope is formed to protect the non-consumable electrode 3 from electrochemical

destruction. The gas bubbles, by means of the grooves 7, are uniformly distributed over the whole surface of the portion of the electrode 3 immersed in the slag bath 5. Next a voltage from an a-c or d-c supply source is applied to the non-consumable electrode 3 and pan 2,

with the consumable electrodes 4 being lowered into the slag bath. The consumable electrodes 4 start to melt down as soon as their lower ends come in contact with the slag bath 5. The molten metal obtained due to the melting of the consumable electrodes is fed into the mold 1 and an ingot 12 is shaped. The consumable electrodes 4 may be made in the form of rods of a different length of steel or alloy or in the form of rods made of powders and lumpy materials through pressing and sintering processes.

The end wall 3b of that portion of the non-consumable electrode which is immersed in the slag bath 5 has a convex or other curvilinear shape to provide for smooth washing of the whole immersed portion of the

non-consumable electrode 3 with the gas bubbles 11.

In FIGS. 4 and 5 is illustrated an embodiment for electroslag casting of hollow ingots which includes a cooled mold 13 and a pan 14 provided with an opening, a consumable electrode 15 and a cooled pan 16 for shaping the inner space of an ingot 17 used as a non-consumable electrode.

The walls of the pan 16 at the level of metal bath 18 and slag bath 19 are provided with channels 20 with openings 21 for feeding the gas from a gas distributor 22.

The channels 20 provided with the openings 21 in the walls of the pan 16 are located tangentially to the axis thereof as can be seen in FIG. 5.

FIG. 4 also shows a power source 23 inserted between the consumable electrode 15 and pan 16. Such a device operates similarly to the above-described device, with the difference being that during the entire process of casting the hollow ingot 17, a mutual displacement of the mold 13 and the pan 14 securing the ingot 17 occurs at a speed close to the speed of lifting of the slag bath 19.

In the above-described embodiments, the immersed portion of the non-consumable electrode is washed with gas flows under a pressure which is not lower than the hydrostatic pressure created by the column of the melt whose height is equal to the length of the portion of the non-consumable electrode immersed in the melt.

The gas flow may be composed of inert gases such as helium and argon, as well as other gases, reagents, gas and gas-and-powder mixtures.

However, in case convective streams are present in the melt, the preliminarily immersed portion of the non-consumable electrode is to be washed with the gas streams under a pressure which can be lower than the hydrostatic pressure created by said melt column.

We claim:

1. A device for electroslag casting of ingots which comprises a mold, a bottom plate therefor, consumable electrodes, a non-consumable cooled metal electrode to be partially immersed in a melt, and an electric current source provided between the non-consumable electrode and the bottom plate, said non-consumable electrode having a a sidewall, an end wall and a bore through which a gas flow passes, the end wall and the sidewall adjacent thereto having grooves, the grooves being provided with openings in communication with the bore, with the grooves serving for guiding a flow of gas bubbles admitted from the openings over the whole surface of the partially immersed non-consumable cooled metal electrode, thus preventing it from electrochemical destruction.

2. The device as claimed in claim 1 in which the end wall of the electrode is convex.
